UNITED STATES PATENT OFFICE.

LYMAN W. MERRIAM, OF FITCHBURG, MASSACHUSETTS, ASSIGNOR OF ONE-HALF TO GEORGE O. ALLEN, OF SAME PLACE.

DESIGN FOR A BOTTLE.

SPECIFICATION forming part of Design No. 25,207, dated March 3, 1896.

Application filed October 8, 1895. Serial No. 565,076. Term of patent 14 years.

To all whom it may concern:

Be it known that I, LYMAN W. MERRIAM, a citizen of the United States, residing at Fitchburg, in the county of Worcester and State of Massachusetts, have invented and produced a new and original Design for Bottles; and I do hereby declare the following to be a full, clear, and exact description of the invention, such as will enable others skilled in the art to which it appertains to make and use the same.

My present invention relates to a new design for a bottle; and the same consists in the novel shape and configuration of the mouth end of the bottle, substantially as will be hereinafter described and claimed.

In the annexed drawing, illustrating my new design, the figure is a perspective view of my newly-designed bottle.

The leading features of my new design for a bottle are as follows: A peripherally-swollen or exteriorly-curved mouth end B is shown at the end of the contracted neck a on the main bottle A. On the said mouth end B is mounted a rounded swollen vertical extension D, which connects with the mouth B by the attenuated connection C, opposite to which, on the outside, is a sharp deeply-cut groove.

What I claim is—

The design for a bottle, substantially as shown and described.

In testimony whereof I affix my signature in presence of two witnesses.

LYMAN W. MERRIAM.

Witnesses:

OSCAR W. WHITE,
FRED E. TASKER.
